UNITED STATES PATENT OFFICE.

ANDERSON C. HECK, OF FINDLAY, OHIO, ASSIGNEE TO THE BUCKEYE TRACTION
DITCHER COMPANY, OF FINDLAY, OHIO, A CORPORATION OF OHIO.

EXCAVATOR.

1,110,931.

Specification of Letters Patent. Patented Sept. 15, 1914.

Application filed August 22, 1913. Serial No. 786,157.

To all whom it may concern:

Be it known that I, ANDERSON C. HECK, a citizen of the United States, and a resident of Findlay, in the county of Hancock and

5 State of Ohio, have invented a certain new and useful Excavator; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention relates to excavators. It is applicable to a variety of forms of excavators, such as rotary or wheel excavators or chain excavators, and in fact the invention may be contained in a great variety of constructions.

20 The invention consists in providing a wheel or chain or other propelling means and buckets located on the propelling means in a stepped and spaced relation to each 25 other.

The invention also consists in providing a means for carrying a plurality of removable buckets located crosswise the path of the propelling means to produce varying 30 widths of excavation.

The invention also consists in providing a means which will enable the material to be removed from the buckets.

35 A structure containing the invention is illustrated in the drawings. This particular construction is shown and described to illustrate the practicability of the invention. The particular structure shown can be greatly modified and yet such constructions may still 40 contain the invention.

In the drawings, Figure 1 is a side view of a part of a wheel in connection with which the invention may be used. Fig. 2 illustrates a vertical sectional view of the 45 part of the wheel shown in Fig. 1. Fig. 3 illustrates a sectional view of one of the side buckets used in connection with the invention. Fig. 4 illustrates a side cutting knife for cutting clearance for the rack, which 50 coats with a gear for propelling the wheel.

1 is a supporting beam for supporting the propelling parts of the excavator.

2 is a propelling shaft. 3 designates gears keyed to the said shaft. The teeth of the 55 gear engage with the racks 4 to cause rota-

tion of the excavating wheel. Bucket cutters 6 and 7 are located on the said excavating wheel. The excavating wheel is steadied by the roller 10.

The excavating wheel comprises a pair of 60 racks 4 secured to annular flanges 8 and 9. The outer edges of the annular flanges extend inwardly toward each other so that the outer edges are nearer together than the inner edges of the said flanges. The bucket 65 cutters 6 are semicylindrical and are disposed in spaced relation along the outer edges of the said flanges. Their edges are bolted to the flanges or secured in any other way desired which will permit their removal. 70 The bucket cutters 6 have sharp edges 12 for cutting the soil. They may be provided with rooters 13 which have upturned sharpened edges which dig into the soil. They are each provided with a bottom 75 14 which closes one end of the semi-cylindrical bucket. The buckets 7 are also provided with a sharp cutting edge 15. The buckets 7 are also semicylindrical and are secured at one side to the flange 8 on one side 80 of the wheel and to the flange 9 on the other side of the wheel by means of bolts or other means permitting the removability of the buckets. They are arranged in stepped relation to the buckets 6 and along the periphery 85 of the wheel. Either or both sets of side buckets may be removed and side cutters shown in Fig. 4, may be inserted in place of the side buckets. The knives 18 have flaring or spoon shaped blades and are secured 90 to the flanges 8 and 9 by means of bolts or other means which will permit their removability. The knives 18 cut a space for clearance of the rack 4 to prevent the same from entering the soil and becoming clogged. 95 When a set of side buckets and a set of knives are used the side buckets 7 and knives 18 are located oppositely on the wheel and alternately with respect to the buckets 6 along its periphery. I have thus provided 100 a means whereby three different widths of excavation may be made by the same excavator according to the arrangement of the buckets and cutters placed upon the wheel.

One side of each bucket 6 is open through 105 which the material is free to fall when a bucket reaches a certain point in the rotation of the wheel. A shield 20 extends to a point where the buckets begin to turn over and prevents the contents of the buckets be- 110

ing lost. The bottom 14 of each bucket 6 extends to the shield 20 and thus prevents loss of the material until the bucket reaches the upper end of the shield 20 when the material drops from the buckets. The flanges 8 and 9 slant outward from the bucket to enable the material contained therein to drop out of the bucket and to fall from the bucket at the upper end of the shield 20. 10. The buckets 7 also being formed of a semi-circular plate permit the material to fall when it reaches a certain point in the rotation of the wheel. The bottoms 17 of the buckets 7 extend to the shield 21. The shields 21 operate in the same way that the shield 20 operates to prevent the soil gathered by the buckets 7 being lost until the soil drops over the upper edge of the shield 21. The upper edge of the shields 20 and 21 20 extend over a belt conveyer 25. The belt conveyer may be propelled by any suitable propelling gear or device such that it will carry away the soil as it falls from the buckets 6 and 7. 25. What I claim as new, and desire to secure by Letters Patent is as follows:

1. In an excavator, the combination of a wheel having flanges, the outer edges of the said flanges being inclined toward each other, buckets comprising semi-circular sheets removably secured to the said flanges, side buckets located alternately to the first

named buckets and along the periphery of the said wheel and removably secured to one of the said flanges.

35

2. In an excavator, the combination of a wheel having flanges, the outer edges of the said flanges being inclined toward each other, buckets comprising semi-circular sheets removably secured to the said flanges, 40 said buckets located alternately to the first named buckets and along the periphery of the said wheel and removably secured to the said flanges, shields extending along the inner edges of the flanges and from a point below the horizontal diameter of the wheel 45 to the dumping point of the bucket, a conveyer for conveying the material from the said buckets.

45

3. In an excavator, the combination of 50 an excavator wheel, a plurality of buckets secured to the said wheel, a plurality of side buckets located alternately to the first named buckets and along the periphery of the said wheel, clearance knives located on 55 the side opposite to the said side buckets and alternate with the first named buckets.

In testimony whereof, I have hereunto signed my name to this specification in the presence of two subscribing witnesses.

ANDERSON C. HECK.
